S. PAVILLARD

TRAIN ACTUATED SIGNAL FOR ROAD AND STREET CROSSINGS

Filed Nov. 3, 1924

Patented May 12, 1925.

1,537,187

UNITED STATES PATENT OFFICE.

SAM PAVILLARD, OF DECATUR, TEXAS.

TRAIN-ACTUATED SIGNAL FOR ROAD AND STREET CROSSINGS.

Application filed November 3, 1924. Serial No. 747,547.

To all whom it may concern:

Be it known that I, SAM PAVILLARD, a citizen of the United States, residing at Decatur, in the county of Wise and State 5 of Texas, have invented certain new and useful Improvements in Train-Actuated Signals for Road and Street Crossings, of which the following is a specification.

My invention relates to signaling devices 10 for street and road crossings and more particularly to train-actuated signals; and the object is to provide a simple rotary signal and simple means for actuating the signal by the wheels of passing trains and which 15 will be positively and certainly actuated whenever a train passes and which will be actuated in plenty of time before the train reaches a crossing to prevent accidents. Other objects and advantages will be fully 20 explained in the following description and the invention will be more particularly pointed out in the claims.

Reference is had to the accompanying drawings which form a part of this application. 25

Fig. 1 is a side elevation of the signaling devices and the means for actuating the signaling devices. Fig. 2 is a plan view of the actuating devices. Fig. 3 is a cross-section, taken on the line 3—3 of Fig. 1. Fig. 30 4 is a cross-section, taken on the line 4—4 of Fig. 1. Fig. 5 is an enlarged detail view of the ratchet mechanism for rotating the signal. Fig. 6 is a detail view of a sounding device to be actuated along with the revolving of the signal. Fig. 7 is a detail view of the wheel-actuated mechanism.

Similar characters of reference are used 40 to indicate the same parts throughout the several views.

In the drawings a rail 1 is shown and a yielding bar 2 is operatively connected to the rail by clamps 3. The bar 2 is carried by the hanger 4 to which the bar 2 is rigidly 45 connected. The bar 2 is yieldable vertically by reason of the spring supports for the hanger 4. Each hanger 4 has a foot piece 5 which rests on top of a plunger 6 and this plunger is supported in the elevated position 50 by a spring 7 which supports the foot piece 5. The plunger 6 is attached to the foot piece 5 and serves as a guide to make the bar 2 move vertically. The spring 7 is supported in a hanger 8 and a tubular guide 9 55 is screwed through the bottom of the hanger 8 for the plunger 6. Both hangers 8 and

their connections are duplicates. The bar 2 is drooped or curved downwardly on top near the ends so that the wheels of the train will run on the bar without knocking. The 60 clamps 3 are merely for holding the bar 2 close to the rail 1. Anti-friction rollers 10 are carried by the bar 2 to prevent friction against the clamps 3. The tendency of the bar 2 is to move slightly in the direction 65 of the moving train. The rollers 10 will cause the bar 2 to move vertically. The bar 2 actuates a lever 11 which is provided with a fulcrum 12 which is rigid with the rail 1. The fulcrum 12 is attached to the 70 rail in the manner as the clamp 3. A foot piece 13 extends under the rail and a strip 14 extends over a portion of the rail flange and is bolted to the foot piece 13. The bar 2 is operatively connected to the lever 11 75 by a U-bolt 15. The U-bolt is attached to the bar 2 by riveting or otherwise and a pin 16 prevents removal of the lever from the U-bolt 15. The U-bolt 15 slides freely on the lever 11. The lever 11 actuates a link 80 bar 17 which is pivotally connected thereto and pivotally connected to a crank 18 which is rigid with a shaft 19 which is provided with bearings 20. The shaft 19 is provided with an upstanding crank 21. A cord or 85 cable 22 is connected indirectly to the crank 21. The cord 21 runs through a sleeve 22 and the cord is intercepted by a spring 23 to give resiliency to the cord. The object is to prevent sudden jerks on the signaling 90 devices when the train wheels strike the bar 2.

The cord 22 runs under an idle pulley 24 and is attached rigidly to the ratchet lever or bar 25 and is extended and attached to 95 the spring 26 which is attached to a rigid bar 27. A spring 28 is attached to the bar 27 and to a compound lever 29 which is provided with a fulcrum 30 which is attached to the lever 25. The lever 29 is 100 pivotally connected to another lever 31 which is adapted to engage and turn the ratchet wheel 32 which is rigid with shaft 33. The signal which is composed of the disks 34 and arms or spokes 35 is rigid with 105 the shaft 33. A spring 36 is attached to the lever 25 and to the lever 29. The spring 28 is generally slack. A pull on the cable or cord or chain 22 will pull down on the lever 25 and also on the lever 29. The spring 110 36 will cause the lever 31 to engage the ratchet wheel 32 and the lever 25 will cause

the ratchet wheel 23 to turn. This will revolve the signal disks 34 by the repeated striking of the bar 2 by the wheels of the train. The two wires 26 and 28 serve to 5 release the lever 29 from the ratchet wheel and to draw the slack out of the cable 22 to prepare for the next stroke. Another 10 object of releasing the ratchet wheel is to permit the signal disks to return to their 15 normal inoperative positions. In order that the disks 34 may come back to the inoperative position, as shown in Fig. 1, one disk may be made heavier than the other. Various changes in the sizes, construction, and arrangement of the several parts may be made without departing from my invention.

In addition to the revolving signal above described, a sounding device is provided. Revolving beaters 36 are mounted on the 20 shaft 33. The beaters 36 are pivotally connected to arms 37 which are rigidly clamped on the shaft 33. A bell 41 is mounted on an upright 38 and a striker or tongue 39 is mounted on the upright 38. A spring 40 is 25 attached to the upright 38 and to the striker 39. The beaters 36 actuate the striker 39 and the spring 40 causes the tongue to strike the bell 41. Whenever the signal disks 34 are revolving, the bell will be sounding.

39 What I claim is,—

1. Signaling apparatus for street and road crossings comprising a revolving shaft and signaling devices revolving therewith, sounding devices consisting of a bell and a 35 spring actuated striker co-operating with said signaling devices, arms actuated by said shaft, pivoted beaters carried by said arms for operating said striker, and means to be actuated by the wheels of a passing train 40 for driving said shaft.

2. Signaling apparatus for street and road crossings comprising a revolving shaft and signaling devices revolving therewith, sound-

ing devices consisting of a bell and a spring controlled striker co-operating with said signaling devices, revolving arms carried by 45 said shaft, and beaters loosely connected to said arms for actuating said striker.

3. Signaling apparatus for street and road crossings comprising a revolving shaft and 50 signaling devices revolving therewith, sounding devices consisting of a bell and a spring controlled striker co-operating with said signaling devices, revolving arms carried by 55 said shaft, beaters loosely connected to said arms for actuating said striker, movable means to be actuated by the wheels of passing trains, and a cable actuated by said movable means for revolving said shaft.

4. Signaling apparatus for street and road 60 crossings comprising a revolving shaft and signaling devices revolving with said shaft, sounding devices consisting of a bell and a 65 spring controlled striker co-operating with said signaling devices, arms carried by said shaft and provided with means for actuating said striker, a ratchet mechanism for revolving said shaft, and means actuated by the wheels of passing trains for operating 70 said ratchet mechanism.

5. Signaling apparatus for street and road crossings comprising a revolving shaft and signaling devices revolving therewith, ratchet mechanism for revolving said shaft, a depressing bar to be actuated by the wheels 75 of passing trains, a hanger carrying said bar and yielding means concealed beneath a railway rail supporting said hanger, clamping devices for guiding the vertical movement of said bar, a crank shaft operatively connected to said bar, and a flexible cable operatively connected to said shaft and to said 80 ratchet mechanism for revolving said shaft.

In testimony whereof, I set my hand, this 15th day of October, 1924.

SAM PAVILLARD.
